UNITED STATES PATENT OFFICE.

ALFRED THOMAS EDWARDS, OF WALSALL, ENGLAND, ASSIGNOR TO JABEZ CLIFF & COMPANY LIMITED, OF WALSALL, STAFFORD, ENGLAND, A COMPANY OF GREAT BRITAIN.

FOOTBALL AND OTHER GAMEBALL.

Application filed January 14, 1922. Serial No. 529,290.

To all whom it may concern:

Be it known that I, ALFRED THOMAS EDWARDS, a subject of the King of Great Britain, residing at Globe Works, Forster Street, 5 Walsall, in the county of Stafford, England, have invented certain new and useful Improvements in Footballs and Other Gameballs; and I do hereby declare the following to be a full, clear, and exact description of 10 the same.

My invention comprises improvements in footballs and other game balls and refers to an improved method of construction of the casing whereby the mouth of the ball is 15 strengthened.

Hitherto there have been two general ways of constructing the cases of footballs, in one of which the mouth of the ball is formed where two sectional pieces of leather 20 are juxtaposed and sewn together at their extremities but being left unconnected at the middle so as to provide the mouth, whilst in the second method of construction one of the sectional pieces has a slit extending for 25 part of its length to provide the mouth. In the first-mentioned method of construction the effective length of the mouth is limited only by the stitching of the two adjacent parts together, and it has been found in 30 practice that this stitching gives way before the ball is otherwise worn out.

The object of the present invention is to overcome these defects and to provide a ball in which the stitching is reduced to a minimum, and in accordance therewith the one 35 sectional piece adjacent the mouth is provided with a slit so as to form the mouth, and the extremities of this piece are also cut in alignment with the mouth slit but without 40 extending thereto. The mouth slit is thus terminated at each end by solid leather which may extend for a distance say of one inch, whilst the slits at the extremities may be of V or other shape, in which case a piece 45 of leather is removed and the adjacent edges then sewn together so as to provide a section of the required shape.

Referring to the accompanying drawings:

Figure 1 is a face view of the outer case 50 of a football according to this invention.

Figure 2 is a fragmental sectional view taken through the sectional piece which contains the mouth.

Figure 3 is a face view of the blank of the sectional piece which contains the mouth. 55

In the construction illustrated upon the accompanying drawings the outer case of the ball is formed in the usual manner from a plurality of sectional pieces indicated by 1.

One of the pieces which forms the outer 60 case, marked 2 is provided with a slit 3 which is centrally disposed in the sectional piece and is adapted to form the mouth through which the inner member or bladder (not shown) is inserted and through which 65 the nipple 4 of the inner member extends for the purpose of inflation.

The extremities of the portion 2 are split at 5 and this split is of V or other shape when the piece is in the flat condition so as 70 to give the proper shape to this sectional piece when it is sewn together with the other pieces.

The split in the sectional piece 2 is reinforced by a piece 6 which extends within 75 the mouth and is secured to the sectional piece 2 by stitching as indicated at 7. This reinforced piece is conveniently formed of leather and is provided with lace holes 8 which correspond with the lace holes 9 in 80 the sectional piece 2.

This sectional piece 2 which carries the mouth is formed from a single piece of leather and it corresponds in shape with a pair of the other sections and thus maintains the balance of the ball. 85

It will be seen that the length of the mouth cannot extend without tearing the solid leather at its extremities, and the sectional pieces of the ball are connected together by stitching in the usual manner. 90

What I claim then is:

1. A game ball having an outer case which consists of a plurality of sectional pieces shaped so as to be curved when in position, 95 one of the sectional pieces having a central slit to form the mouth, and a V-shaped slit at each extremity extending towards but not extending to the central slit, to allow this sectional piece to take up its curved form. 100

2. A game ball having an outer case which consists of a plurality of sectional pieces shaped so as to be curved when in position, one of the sectional pieces having a central slit to form the mouth, a reinforcing piece 105 extending over the surface of the slit sec-

tional piece and around the slit therein, and a V-shaped slit at each extremity extending towards but not extending to the central slit, to allow this sectional piece to take up its 5 curved form.

3. A game ball having an outer case which consists of a plurality of sectional pieces, one of the sectional pieces corresponding in shape with a pair of the other sectional 10 pieces and having a central slit to form the mouth and a slit at each extremity extending towards, but not as far as, the central slit.

4. A game ball having an outer case which 15 consists of a plurality of sectional pieces, one of the sectional pieces corresponding in shape with a pair of the other sectional pieces and having a central slit to form the mouth and a slit at each extremity in alignment 20 with the central slit but not extending thereto.

5. A game ball having an outer case which consists of a plurality of sectional pieces, one of the sectional pieces corresponding in 45 shape with a pair of the other sectional pieces and having a central slit to form the mouth, and a V shaped slit at each extremity extending towards but not extending to the central slit.

30 6. A game ball having an outer case which consists of a plurality of sectional pieces,

one of the sectional pieces corresponding in shape with a pair of the other sectional pieces and having a central slit to form the mouth, a reinforcing piece extending over 35 the surface of the slit sectional piece and around the slit therein, and a slit at each extremity extending towards, but not as far as, the central slit.

7. A game ball having an outer case which 40 consists of a plurality of sectional pieces, one of the sectional pieces corresponding in shape with a pair of the other sectional pieces and having a central slit to form the mouth, a reinforcing piece extending over 45 the surface of the slit sectional piece and around the slit therein, and a slit at each extremity in alignment with the central slit but not extending thereto.

8. A game ball having an outer case which 50 consists of a plurality of sectional pieces, one of the sectional pieces corresponding in shape with a pair of the other sectional pieces and having a central slit to form the mouth, a reinforcing piece extending over 55 the surface of the slit sectional piece and around the slit therein, and a V shaped slit at each extremity extending towards but not extending to the central slit.

In witness whereof I affix my signature.

ALFRED THOMAS EDWARDS.
